Calif., a partnership

Application September 5, 1950, Serial No. 183,128

2 Claims. (Cl. 20—7)

1

This invention relates to flooring and more particularly to an inexpensive and easily laid prefabricated flooring block.

In one aspect, the invention contemplates a flooring block of rectangular shape comprising a plurality of parallel adjoining rows of wood strips of random length and flexible means joining the strips in block form. The flexible means may take the form of a waterproof backing, for example a saturated building felt, or of a flexible adhesive disposed between the abutting edges of the several pieces forming the individual block. In one form of the invention at least one of the several rows making up each block consists of two or more separate pieces of wood in end-to-end abutment, and in the preferred form of the invention all of the rows in each block consist of two or more separate lengths of wood. The advantage of this construction will become apparent.

Flooring in accordance with the invention has two major advantages. The blocks as described above may be and are fabricated exclusively from wood presently designated in the trade as "scrap" or "waste." Scrap generally constitutes strips of from about two to eight inches in length and which at present have no value for flooring purposes. The use of this otherwise waste material represents not only a conservation but also an appreciable economy. For example, hardwood scrap can be purchased in the market for about \$.02 a square foot as compared to something in excess of \$.16 per square foot for longer strips of the same wood.

Not only is it possible to use scrap in the flooring block of the invention but it is desirable to do so. One of the principal recommending features of the present block is its flexibility, as a result of which the block shapes itself to the contours of the sub-flooring. In this respect the block is similar to asphalt tile in avoiding any high spots or protruding edges as a result of unevenness in the sub-flooring, but differs from any wood flooring presently in use. This desirable flexibility is enhanced by use of scrap or waste. By assembling each block so that two or more separate end-to-end abutting pieces go into one or all of the parallel rows forming the block, flexibility is achieved longitudinally as well as transversely of the rows.

The invention will be clearly understood from the following detailed description thereof taken in relation to the accompanying drawing wherein:

Fig. 1 shows a section of floor laid with blocks in accordance with the invention;

Fig. 2 is a sectional elevation taken through

one form of the block of the invention as on the line 2—2 of Fig. 1;

Fig. 3 is a similar sectional elevation of another form of the invention; and

Fig. 4 is a sectional elevation of still another form of the invention as taken on the line 4—4 of Fig. 1.

In Fig. 1 a number of blocks 10, 11, 12, etc., are laid on and bonded to a concrete sub-flooring 14 with mastic 15. The blocks may be laid as shown so that the parallel rows of each block are transverse to the parallel rows of an adjoining block in the conventional parquet manner or in any other desired pattern or configuration.

One form of the block of the invention is shown in sectional elevation in Fig. 2 as taken on the line 2—2 of Fig. 1. Referring to Figs. 1 and 2, the block 10 comprises four rows 16, 17, 18, 19 of wood strips with each row comprising two separate strips in end-to-end abutment and with the point of abutment of the strips in one row being spaced from the point of abutment of the strips in an adjoining row. This embodiment makes use of conventional tongue and grooved strips and after assembly of the block the exposed edges of the outer strips are faced off and squared to fit against an adjoining block. The several rows 16, 17, 18, 19 are bonded on a single, flexible, waterproof backing 20. The block 10 may be laid on the concrete sub-flooring 14 with a layer 15 of mastic and, because of the flexibility mentioned above, shapes itself to the contour of the sub-flooring insuring a smooth joint with an adjoining block.

This is an important consideration when flooring a concrete slab since the inevitable surface variations of the slab will result in projecting edges, unstable blocks, etc., if a more rigid form of flooring is used.

A similar block 22 is shown in Fig. 3 and comprises four parallel rows 23, 24, 25, 26 preferably consisting of two separate strips of wood in each row and bonded to a flexible backing 28. The block 22 of Fig. 3 differs from the block 10 of Fig. 2 in the absence of tongue and groove connection between adjoining rows of the block. Such tongue and groove connection is not necessary to the practice of the invention if a backing sheet is employed since the blocks are held in edge-to-edge abutment by the backing. The block 22 may be laid with equal facility and will present the same appearance as the block 10 of Fig. 2 even on a concrete surface having the usual uneven contour.

A somewhat different embodiment of the invention is shown in Fig. 4 as taken on the line 4—4 of Fig. 1. The block 12 as shown in trans-

verse section in Fig. 4 comprises parallel rows 30, 31, 32, 33 with tongue and grooved adjoining edges and faced outer edges. In this block the waterproof backing used in the blocks 10 and 22 is eliminated and a flexible adhesive 34 is applied in the engaging tongues and grooves to hold the rows together in flexible relationship. Many rubber base flexible adhesives, available commercially, are satisfactory for this use. As shown in Fig. 1 the row 32, for example, is composed of two separate end-to-end abutting pieces. With the longitudinal edges joined by a flexible adhesive, no union is necessary between the abutting ends of the several pieces in a given row. As in the foregoing embodiment, preferred practice in fabricating a block of this type comprises providing at least two separate end-to-end abutting pieces in each block row.

The block 11 of Fig. 1 illustrates the possibility of employing three or even four separate pieces in a single row, the greater the number of pieces imparting additional flexibility to the block.

The flooring blocks of the present invention have a great many advantages, some of which have been pointed out above. Thus the block makes use of wood which is ordinarily discarded and hence is very inexpensive with regard to materials employed. Secondly, the block has a degree of flexibility not heretofore achieved in wood flooring which permits it to shape itself to sub-flooring contours and which in the preferred form of the invention, wherein each adjoining row of a given block constitutes two or more separate end-to-end abutting pieces, has a flexibility along axes normal to each other. Moreover, the block is very easily laid because of this flexibility and for the further reason that no interconnection is required between adjoining blocks. Since no nails are required in laying the blocks of the invention, their effective life is much greater than ordinary wood flooring of the same thickness. Particularly is this true in the embodiment of Fig. 3 wherein the entire thickness of the wood strips is available for wear.

The flooring as shown and described readily adapts itself to continuous mass scale production which is preferably carried out in producing blocks of the types shown in Figs. 2 and 3 substantially as follows. A strip of flexible backing of the appropriate width is carried continuously past an operator who applies a coating of mastic or other bonding agent thereto. A second operator having access to a supply of random length waste strips places these on the backing in a continuous fashion and in four adjoining rows as shown in the drawing. This operator need only take care that the end-to-end abutment of adjoining strips in one row does not coincide with the end-to-end abutment of adjoining strips in an adjacent row. To fabricate the preferred form of the invention this operator should also make sure that in any unit length, two or more strips are in end-to-end abutment in each row so that when this unit length is cut from the continuous length it will have the maximum longitudinal flexibility as described above. In the next operation, which may be carried out manually or automatically, the strips are urged together so that they will be in close relationship before the bonding agent has set. The continuous strip thus formed is thereafter cut into unit lengths and the units are stored for a period while exerting a bonding pressure between the wood and the backing. This storage is conveniently accomplished by stacking a number of units and applying a weight to the top unit.

A similar method may be used to fabricate the embodiment of the invention shown in Fig. 4. In this method a carrier strip, which may be canvas or some other form of backer, is conveniently employed to carry the work past successive operators, the first of which may apply a flexible adhesive as a continuous coating or in separate globules in the grooves or on the tongues of the separate pieces of wood. A second operator then forms these pieces into a continuous length of the appropriate number of parallel rows, the several rows are urged together as in the above described method and the continuous length is cut into units of the appropriate length. The cutting is conveniently done after the bonded rows are discharged from the carrier belt.

The blocks may be made in substantially any size and including any number of rows. The width is conveniently determined as a multiple of the width of the individual strips and the length is determined only by convenience in handling. Any method may be used for fabricating the block of the invention, those described being merely presently preferred methods.

I claim:

1. A rectangular parquet flooring block for forming with other similar blocks a covering for a subfloor and comprising a flexible backing strip coextensive with the block, a plurality of juxtaposed wood pieces affixed to the backing strip and arranged thereon in a plurality of rows abutting but not rigidly fastened at their sides so that the block is flexible in a direction across the rows, each of the rows being composed of a plurality of juxtaposed pieces having abutting but unjoined planar ends so that the block is flexible in the direction of the rows, with the abutting ends in one row staggered with respect to the abutting ends in an adjacent row so that the flexibility in the direction of the rows is limited, the block tending to conform in both directions to the irregularities of a subfloor on which it is laid with the flexible backing strip downward.

2. A rectangular parquet flooring block for forming with other similar blocks a covering for a subfloor and comprising a flexible backing strip coextensive with the block, a plurality of juxtaposed wood pieces affixed to the backing strip and arranged thereon in a plurality of rows abutting but not rigidly fastened at their sides so that the block is flexible in a direction across the rows, each of the rows being composed of a plurality of juxtaposed pieces of random length having abutting but unjoined planar ends so that the block is flexible in the direction of the rows, with the abutting ends in one row staggered with respect to the abutting ends in an adjacent row so that the flexibility in the direction of the rows is limited, the block tending to conform in both directions to the irregularities of a subfloor on which it is laid with the flexible backing strip downward.

HERBERT G. MACDONALD.
